UNITED STATES PATENT OFFICE.

DEAN KEYES ROBINSON, OF BALTIMORE, MARYLAND.

PIVOT LATHE FOR WATCHMAKERS.

Application filed August 5, 1922. Serial No. 579,859.

To all whom it may concern:

Be it known that I, DEAN K. ROBINSON, a citizen of the United States, and a resident of Baltimore, in the county of Baltimore 5 City and State of Maryland, have invented a new and Improved Pivot Lathe for Watchmakers, of which the following is a full, clear, and exact description.

This invention relates to pivot straightening devices and lathes for horological balance wheels and train gears, and has reference more particularly to a lathe having one pivot supporting member movable along the axial plane of the pivot, and another movable 15 in a plane transverse to the axis of the pivot.

An object of this invention is to provide a new and improved device for facilitating the inspection, straightening, adjusting, refinishing and polishing of the pivot points of horological balance wheels and train gears.

Another object is to provide a device of the character stated, which has a pivot supporting member movable on the axial plane of the pivot and the other pivot supporting member movable in a plane transverse to the axial plane of the pivot.

Further objects will appear as the specification proceeds, of which the drawings form one part, it being understood that the same illustrate only one example of the invention, since it could be easily changed without departing from the spirit of the 35 invention.

In the drawings:—

Figure 1 is a side view of the device showing certain of its parts in section to more clearly illustrate the same;

Figure 2 is a top view of the device;

Figure 3 is an end view of the device showing the balance wheel supporting end;

Figure 4 is a detail view of Figure 3 with one supporting member removed; and

Figures 5 and 6 are detail views of an element to be hereinafter referred to.

In carrying out my invention in accordance with the illustrated example, a base or bench plate 1 is provided with openings 2 adapted to receive screws 3 by means of which it is secured to the work bench A. Said bench plate 1 also presents a pair of bores 4 adapted to receive pins 5 forming a part of frame 6, which presents a substantially U-shaped structure with one leg formed with a head 7 through which extends

a bore 8 adapted to slidably receive a pintle 9. The other leg of said frame presents a pair of threaded openings 10 and 11 adapted to receive a pivot screw 13 and a clamping screw 14, respectively, by means of which bar 12 is rockably held against said frame.

To the upper end of bar 12 is secured a blade 15 provided with a series of openings or pivot holes 16, each of which can be brought in line with the axis of pintle 9 by swinging the bar on pivot 13 and clamping the same against movement after the desired adjustment has been made.

The blade 15 is preferably thin to permit a train gear or balance wheel pivot to project outwardly when inserted in one of said holes in order to have its projecting point inspected, straightened or refinished. The pintle 9 has one end threaded to receive a nut 17, preferably beveled adjacent its inner end and slotted at its opposite end, as at 18 (Figure 4), for providing tool engaging members to effect its screwing or unscrewing on the pintle. At the other end of said pintle is arranged a head 18 for moving the pintle in said bore 8 and at a point intermediate its ends has a projection or collar 19, also preferably beveled for a purpose hereinafter set forth.

Said pintle revolvably carries between its threaded end and the collar 19 a sleeve 20 having a grooved pulley 21 at one end and a collar 22 at the other. The bore of said sleeve flares outwardly adjacent its ends to snugly engage the beveled collar 19 and the nut 17. The threaded end of the pintle has in its center a pivot bearing notch or center point, whereby a train gear can be interposed and rotatably held between the pintle and the blade 15.

The collar 22 is formed with a slot 23 which preferably has a curved end wall 33 and which splits a portion of said collar into two parts 24 and 25, through which passes an opening 26 adapted to receive the shank of a fork 27. In said slot 23 is arranged a flexible bar 34 which normally presses against the shank 27 when the same is inserted in the openings 26, and thereby the same is held in place against displacement. The fork 27 is adapted to engage the spokes of a balance wheel or the like, and through it the balance wheel is made to revolve with the sleeve 20.

The head 7 has a threaded opening 28 intersecting the bore 8 and said opening is

adapted to receive a screw 29 which is screwed tight against the pintle 9 to hold the latter in place once it has been moved toward the blade 15 to engage a train gear interposed between the blade and the pintle.

When the pivot point of a balance wheel is desired to be inspected, straightened or repaired, the same is inserted in one of the openings 16, which by means of adjusting screw 14 is brought directly in line with the axis of the pintle and the pintle is then moved toward the other pivot of the train gear to engage and hold it. The fork 27 is made to engage one of the spokes of the balance train gear placed in the lathe for adjustment, the screw 29 is tightened against the pintle 9 and the same is prevented from moving rearwardly until so desired.

The sleeve 20 is then rotated by means of a bow-arm or other suitable means well known in the horological art and thereby the rotation of said sleeve is imparted through the fork 27 to the train gear interposed between the pintle 9 and the blade 15.

I would state in conclusion that while the illustrated example constitutes a practical embodiment of my invention, I do not limit myself strictly to the exact details herein illustrated, since, manifestly, the same can be considerably varied without departing from the spirit of the invention as defined in the appended claims.

I claim:

1. In a device of the character described, a frame, a pintle mounted on the frame for longitudinal adjustment and having one end thereof provided with work engaging means, a clamping screw for securing the pintle in adjusted position, a blade adjustably mounted on the frame and having a plurality of holes selectively cooperable with the work engaging means of the pintle for supporting the work for rotary movement while leaving the same accessible, and means mounted on the pintle for imparting rotary movement to the work.

2. In a device of the character described, a frame, a pintle mounted on the frame for longitudinal adjustment and having one end

thereof provided with work engaging means, a clamping screw for securing the pintle in adjusted position, a blade adjustably mounted on the frame and having a plurality of holes selectively cooperable with the work engaging means of the pintle for supporting the work for rotary movement while leaving the same accessible, said pintle having a portion externally threaded and being provided with a beveled collar, a sleeve fitted on the pintle and having one end shaped to rotatably fit on said beveled collar, a nut engaged with the threaded portion of the pintle and having a beveled end, the sleeve having a beveled portion adapted to rotatably fit the inner end of the nut, a pulley formed on the sleeve and means for transmitting the rotary movement of the sleeve to the work.

3. In a device of the character described, a frame, a pintle mounted on the frame for longitudinal adjustment and having one end thereof provided with work engaging means, a clamping screw for securing the pintle in adjusted position, a blade adjustably mounted on the frame and having a plurality of holes selectively cooperable with the work engaging means of the pintle for supporting the work for rotary movement while leaving the same accessible, said pintle having a portion externally threaded and being provided with a beveled collar, a sleeve fitted on the pintle and having one end shaped to rotatably fit on said beveled collar, a nut engaged with the threaded portion of the pintle and having a beveled end, the sleeve having a beveled portion adapted to rotatably fit the inner end of the nut, a pulley formed on the sleeve and means for transmitting the rotary movement of the sleeve to the work, said means including a collar carried by the sleeve having a longitudinal opening, and a transverse slot intersecting the opening, a fork carried in the longitudinal opening of the collar and adapted to be engaged with the work, and a resilient bar arranged in the slot and adapted to press against the fork to hold the same in position.

DEAN KEYES ROBINSON.
